MACHINE FOR EXPANDING SHEET METAL.

1,195,228.

Specification of Letters Patent. Patented Aug. 22, 1916.

Application filed August 29, 1913. Serial No. 787,389.

To all whom it may concern:

Be it known that I, HENRY C. HERR, a citizen of the United States of America, residing at Pittsburgh, in the county of Allegheny and State of Pennsylvania, have invented certain new and useful Improvements in Machines for Expanding Sheet Metal, of which the following is a specification, reference being had therein to the accompanying drawings.

The invention relates to machines for expanding sheet metal and more particularly to a construction adapted for the differential expansion of a sheet metal blank as hereinafter set forth.

In the drawings: Figure 1 is a plan view of the machine. Fig. 2 is a longitudinal section therethrough. Fig. 3 is a cross section. Fig. 4 is an enlarged section of a portion of Fig. 3; and Fig. 5 is a diagram, showing the path of travel of the blank-carrying chains.

My improved machine is particularly designed for use in expanding stranded metal sheets which are provided with unslotted margins. Such sheets cannot be expanded merely by drawing the opposite margins of the sheet apart, for the reason that this would result in a longitudinal contraction of the expanded, stranded portion and the consequent buckling of the unexpanded margins. The longitudinal contraction could be avoided by the elongation of the strands by the drawing process, but this would be insufficient, as it would result in weakening the sheet particularly along the line of division between the stranded and unstranded portions thereof.

My improved machine is one designed to differentially expand the stranded product, which is passed therethrough, and further to differentially elongate the strands so as to compensate for their angular movement and to prevent longitudinal contraction.

The expanding machine may be either separate from or forming a continuation of the slitting machine, in which the sheet is suitably stranded. As shown, the slitting machine is adjacent to the expanding machine and the stranded product is delivered directly to the latter.

The expanding machine comprises a suitable frame A, upon which is mounted a series of rolls B B' B², etc., arranged in

pairs above and below the plane of the sheet. 55 There is also arranged upon opposite sides of the frame traveling chains C, which extend in divergent paths and are provided with edge grippers D for engaging the margins of the sheet. These chains with their 60 grippers are so guided that during a portion of their forward movement they are arranged parallel to the edges of the unexpanded sheet, the grippers being engaged with the sheet at this time. The chains and 65 their grippers are then guided through divergent paths and continue in this direction until the expansion is completed, after which they again pass into parallel orbits, the grippers being disengaged from the sheet during 70 this portion of its movement.

The expansion of the stranded sheet is effected by the drawing apart of its opposite margins by the grippers and chains. This expanding effect is not, however, continuous in all portions of the sheet at the same time but alternates between different portions. Furthermore, the elongation of the strands, which is necessary to the expansion of the sheet, avoiding longitudinal contraction, occurs during the interval in which said portions are not laterally expanded, and is effected by the successive action of the rolls B B' B², etc. This alternate expansion of different portions of the 85 sheet is effected by the following construction:—E and F are complementary tongue and groove guides arranged respectively below and above the plane of the sheet and so fashioned as to engage with a single line 90 of strands and to prevent lateral movement thereof. This engagement of the guides with the strands is possible by reason of the fact that during the slitting or stranding of the sheet, alternate strands are deflected into different planes, as shown in Fig. 4. Thus when the stranded sheet is delivered to the expanding machine, the guides E and F will register with a certain line of strands, and, after engagement therewith, will prevent lateral movement of said strands from the plane of the guides. The guides E and F are arranged upon opposite sides of the machine and run parallel to the direction of the divergent portions of 100 the chain C, but instead of being continuous these guides are interrupted opposite each of the pairs of rolls B B' B², etc. Thus when

the sheet is in engagement with the guides only the stranded portion between said guides is capable of lateral expansion, as the portions between the guides and the chains move in a path parallel to the latter. As soon, however, as the guides terminate, the chains continuing in the same divergent paths will exert a tension on the entire sheet, which will expand the portions outside of the guides as well as the central portion. During this interval the rolls will engage the central portion of the sheet and by their drawing action will elongate the strands thereof, so as to compensate for the longitudinal contracting effect produced by the lateral expansion. The sheet will then again engage with another section of the guides, which will confine the expansion to the central portion, and in this manner the sheet is alternately engaged with the guides and by the rolls until completely expanded.

Inasmuch as the sections occupied by the guides are of greater length than the portions in which the rolls are located, the maximum expansion effect is produced in the central portion of the sheet or that portion between the guides, while the outer portions adjacent to the unslotted margins are but slightly expanded. To avoid any marked difference between these portions, the rolls B B' B², etc., instead of being true cylinders, are slightly bulging in the center, so that the maximum elongating or drawing effect on the strands is at the center and from that point is progressively diminished toward the opposite edges. A further effect of this construction is that the central portion of the sheet is effectively held from lateral movement during the interval in which the guides are not in engagement, while the portion from the center toward the margins of the sheet are clamped to a lesser degree by the rolls, permitting of the differential expansion as previously described.

In more specific construction, the machine comprises guides G for the chains and grippers, which are grooved to form channels for rolls H, I and J. Two of these rolls serve to guide the chain through a path corresponding to the channel, while the third roll is attached to the movable jaw of the gripper, and actuates the same for engagement and disengagement from the roll. This jaw is preferably provided with a pin K, which pierces the sheet metal in the marginal portions of the blank and engages a recess L in the lower jaw member. The movement of the jaw is controlled by the shape of the groove or channel, which is suitably cammed at certain points.

The guides E and F are secured, the one to the bed beneath the work and the other to cross bars M passing over the work between the guides G. The degree of expansion

may be altered by adjustment of the angles of the guides, and to this end they are adjustably secured to the cross bars M by bolts N passing through slots O in said bars, while the lower guides E are correspondingly adjustably bolted to the bed. The rolls B are driven by any suitable drive mechanism (not shown).

In operation, the slotted and stranded blank is delivered from the slitting machine 75 on to the frame A, where it is engaged, first, by the grippers D upon that portion C' of the chain C which is traveling parallel to the edge of the blank. The blank then passes into engagement with the guides E 80 and F, which initiate the expanding operation, and it then passes alternately to the rolls B and succeeding sections of the guides until the expansion is completed. At the end the fully-expanded blank passes between 85 the parallel portions C² of the orbits of the chain where it is subjected to the action of crowned compression rolls Q. These rolls only cover the expanded portion of the sheet and their function is to harmonize the differential thickness, elongation and lateral expansion of the sheet, so that when it is 90 disengaged from the chains its sides will be parallel and the stresses due to the expanding operation relieved, permitting the sheet 95 to lie flat. The grippers D are then disengaged from the edges of the sheet, and a set of rolls Q' which extend completely across the expanded portion and unexpanded margins will deliver the sheet in a flattened condition. 100

As before stated, the rolls B B', etc., are slightly crowned, so as to produce the greatest pressure at the center of the sheet and the portions which extend beyond the guides 105 E and F are cut away at R to relieve pressure on that portion of the blank.

I claim:

1. A machine for expanding sheet metal, comprising constantly-operating means for laterally expanding a stranded sheet, and coacting means for confining the expansion to different portions of the sheet.

2. A machine for expanding sheet metal, comprising means for constantly drawing 115 apart opposite edges of a stranded sheet, and coacting means for distributing the expansion differentially throughout the sheet.

3. A machine for expanding sheet metal, comprising means for constantly drawing 120 apart opposite edges of a stranded sheet, and coacting means for distributing the expansion successively between different portions of said stranded sheet.

4. A machine for expanding sheet metal, comprising means for constantly drawing 125 apart opposite edges of a stranded sheet, coacting means for successively limiting the expansion to a central portion of said sheet, and means for successively rolling said cen- 130

- ter portion to elongate the strands thereof and to distribute the lateral expansion to the outer portions of said sheet.
5. A machine for expanding sheet metal, comprising means for constantly drawing apart opposite edges of the stranded sheet, interrupted guides engaging a line of strands in said sheet to limit the expansion on one side thereof, and means intermediate said guides for elongating the strands of the expanded portion.
6. A machine for expanding sheet metal, comprising means engaging opposite edges of a stranded sheet for advancing the same in divergent planes and coacting guides arranged above and below said sheet for engaging a deflected line of strands and for guiding the sheet thereby during its advancement.
- 20 7. A machine for expanding sheet metal, comprising grippers for engaging opposite edges of a stranded sheet, means for causing said grippers to travel in divergent planes, guides for engaging separate lines of deflected strands in said sheet to direct the same during advancement and to confine the expansion to one side of said guides, and means intermediate said guides for engaging the expanded portion and elongating the strands thereof.
8. A machine for expanding sheet metal, comprising a pair of endless traveling chains, grippers secured to said chains and adapted to engage opposite edge portions 35 of a stranded blank, and means for guiding said chains parallel to the direction of travel of the blank during the periods when the blank is being engaged and disengaged, and through divergent paths during the period 40 of engagement.
9. A machine for expanding sheet metal, comprising a pair of endless chains, grippers mounted on said chains, guides for said chains directing the same through parallel 45 paths at opposite ends and through divergent paths intermediate said ends, and cams coöoperating with said grippers to engage and disengage the same with the opposite edges of a stranded sheet and respectively 50 in the parallel portions of their travel at opposite ends.
10. A machine for expanding sheet metal, comprising means for gripping opposite edges of a stranded sheet and for advancing 55 the same in divergent planes, interrupted guides engaging lines of deflected strands and extending parallel to the edges of said
- sheet, whereby the expansion is limited to the portion intermediate said guides, and means operating in the spaces between said interrupted guides for elongating the strands of the expanded portion, while permitting the expansion of the portion previously held from expansion by said guides.
11. A machine for expanding sheet metal, comprising means for differentially expanding a slotted sheet, and means for differentially elongating the strands of said sheet to compensate for said expansion.
12. A machine for expanding sheet metal, comprising means for differentially expanding the slotted portion of a sheet having an unslotted margin, and means for differentially elongating the strands of the sheet to compensate for said expansion without longitudinal contraction.
13. A machine for expanding sheet metal, comprising means for differentially expanding a slotted sheet, and crowned compression rolls for differentially thinning and elongating the strands of said sheet to compensate for said differential expansion.
14. A machine for expanding sheet metal, comprising a series of crowned rolls for advancing and differentially elongating the strands of a slotted sheet, coöperating means for differentially, laterally expanding said sheet in proportion to the differential elongation of the strands thereof, and crowning rolls engaging the expanded portion of said sheet at the completion of the expanding operation, operating to harmonize the differential thickness and elongation to deliver a flat sheet with parallel edges.
15. In a machine for expanding sheet metal, the combination with means for differentially expanding a stranded sheet, of crowning rolls engaging said sheet at the completion of the expansion thereof, operating to harmonize the thickness of the sheet with the differential expansion thereof.
16. In a machine for expanding sheet metal, means for drawing apart opposite edges of the stranded sheet, means for confining the expansion of the sheet to one side of said means, and means for adjusting said means for confining the expansion to alter the degree of expansion of said sheet.
